UNITED STATES PATENT OFFICE.

ALONZO W. RICE AND PETER LANDAKER, OF EUREKA SPRINGS, ARKANSAS.

BUSTLE.

SPECIFICATION forming part of Letters Patent No. 352,427, dated November 9, 1886.

Application filed January 13, 1886. Serial No. 188,431. (No model.)

To all whom it may concern:

Be it known that we, ALONZO W. RICE and PETER LANDAKER, citizens of the United States, residing at Eureka Springs, in the county of Carroll and State of Arkansas, have invented a new and useful Improvement in Bustles, of which the following is a specification, reference being had to the accompanying drawings.

10 Our invention relates to improvements in bustles; and it consists of the peculiar and novel construction and combination of parts, substantially as hereinafter fully set forth, and specifically pointed out in the claims.
15 The primary object of our invention is to provide a device of the class named which shall be very simple, strong, and durable in construction, very light, so as to add very little additional weight to the apparel of the
20 wearer, thoroughly effective for the purposes designed, and very cheap and inexpensive in the manufacture and sale.

The bustle proper is made or formed in one piece of pliable or yielding material, (rubber,) 25 so that it can be adjusted to accommodate itself to different shapes and forms of persons. The yielding rubber serves to properly support the clothing, and when they are once properly and neatly arranged or disposed on 30 the bustle, the latter, by its peculiar construction and arrangement, serves to properly support and retain the clothing in place. The rubber will yield to prevent breaking when any undue strain or pressure is brought thereon, 35 and it has sufficient rigidity and resistance to uphold clothing of ordinary weight. The rubber is non-corrosive, and consequently will not soil, deface, or otherwise injure the clothing, and the device is provided with suitable suspending bands or straps, all as hereinafter described.

In the accompanying drawings, Figure 1 is a plan view of our improved bustle. Fig. 2 is a vertical transverse sectional view thereof on 45 the line $x-x$ of Fig. 1, and Fig. 3 is a detail view in front elevation of the bustle proper with the suspending and retaining bands removed. Fig. 4 is an enlarged perspective view of the bustle.

50 Referring to the drawings, in which like letters of reference denote corresponding parts in all the figures, A designates our improved

bustle, that has a supporting-body, B, a series of radiating arms or supports, C, a suspending-band, D, connected to the body B, and a retaining-strip, E, connected to the outer ends of the radial supports C, the particular arrangement and peculiar construction of the several parts above noted being hereinafter described more fully and in detail.

The body B comprises an upper and lower longitudinal bar, b b' , respectively, and end and intermediate cross or transverse bars, b^2 b^3 , that are disposed in vertical positions at right angles to the horizontal longitudinal bars b b' , 65 and are formed or molded in one piece or integral therewith. The body is thus made very light, strong, and simple in its construction, and it is curved longitudinally to fit the shape of the wearer, or it can be bent and adjusted 70 to accommodate forms of variable shapes and proportions, owing to the pliability of the material of which it is composed.

The supports or arms radiate or project rearwardly from the curved or segmental body B, 75 and they are formed in a single piece therewith. The said arms or supports are made of different lengths from the middle of the body to the ends thereof, the middle arms being longer than the two arms on opposite sides 80 thereof, and the latter being longer than the arms on the sides thereof toward the ends of the body, and so on. An even and neat fit or appearance of the apparel supported by the bustle is thus insured, and the supports are 85 curved downwardly from the points where they join the body to the outer extremities, as shown in Fig. 2.

The lower outer ends of the longitudinally-curved tangential supports or arms are braced 90 by horizontally-disposed brace-arms f , that are formed integral with the lower longitudinal bar, b' , of the body, and the outer ends of said arms or supports, which are further strengthened by transverse diagonal braces g , that are 95 joined and formed with the supports C and brace-arms f at the middle of the former and near the inner ends of the latter. (See Fig. 2.)

It will thus be seen that we provide a bustle that is similar to an open frame, and that the same is very light, simple, strong, and durable in its construction. The several parts are molded or formed in one homogeneous mass of rubber that possesses the requisite resiliency

to yield under undue strain or pressure, while it possesses rigidity to properly support the ordinary quantity of apparel.

The device can be manufactured very rapidly, and it is cheap and inexpensive. The suspending-band D is passed through and between the vertical bars of the body, and either securely connected thereto or left free thereof without securing devices, the ends of the band 10 being extended to pass around the waist. The retaining-strip E is connected to the free ends of the curved tangential supports by stitching, as shown, or other suitable securing means, and the ends of the strip are permanently connected to the suspending-waistband. This 15 strip E serves to keep the supports in proper relative position, and tends to relieve them of undue lateral strain.

Having thus described our invention, what 20 we claim is—

1. A bustle consisting of pliable rubber and comprising a curved body having the sides *b* and *b'* and connecting-bars *b²* *b³*, the radial curved arms or supports *C*, the brace arms *f* 25 intermediate of the outer ends of the radial arms and the lower side of the body, and the diagonal braces *g*, connecting the radial and

brace arms, substantially as described, for the purpose set forth.

2. A bustle consisting of rubber and comprising 30 a curved body, the radial curved arms, the brace-arms intermediate of the outer ends of the radial arms and the body, the waistband *B*, connected to the body, and the band *E*, secured to the outer ends of the radial arms 35 and the waistband, substantially as described, for the purpose set forth.

3. A bustle consisting of pliable or yielding rubber and comprising a curved body having the connected sides *b* and *b'*, the radial curved 40 arms *C*, made gradually shorter from the middle of the body toward the ends thereof, the braces intermediate of the body and outer ends of the arms, and the waist and connecting bands secured to the body and the arms thereof, 45 respectively, substantially as described.

In testimony that we claim the foregoing as our own we have hereto affixed our signatures in presence of two witnesses.

ALONZO W. RICE.
PETER LANDAKER.
